UNITED STATES PATENT OFFICE.

JOSEPH SAMSONOFF, OF NEW YORK, N. Y.

DRAFTING INSTRUMENT.

No. 918,599.

Specification of Letters Patent.

Patented April 20, 1909.

Application filed February 2, 1907. Serial No. 355,347.

To all whom it may concern:

Be it known that I, JOSEPH SAMSONOFF, a subject of the Czar of Russia, residing at the city of New York, county and State of New York, have invented a new and useful Improvement in Drafting Instruments, of which the following is a specification.

This invention relates to improvements in drafting instruments and particularly to 10 that class of drawing instruments, which is used for obtaining aliquot parts of angles.

On account of the fact, that the ratio of the diameter of a circle to its circumference is a mixed number, consisting in part of a 15 whole number, and in part of a decimal fraction, it is, as is well known, practically impossible to calculate accurately more than a few divisions of a circle, such parts as can not be so calculated are still more difficult to 20 measure, in fact we have no accurate and correct instruments for laying off these odd divisions. As an angle is a section of a circle subtended by two of its radii and is measured by the intercepted arc, the same 25 difficulty is to be surmounted in dividing it. So much is this so, that draftsmen and designers often find it a long tedious job to lay off such divisions. And so, much valuable time and labor are expended.

30 The object of my present invention is to produce such an instrument as will by proper application remedy this difficulty.

The object of the invention is also by 35 means of a straight line ruler, and a lateral extension, having a curved edge, on one side thereon, to provide an instrument of the character aforesaid.

The object of the invention is also by 40 means of a straight line ruler, having a graduated edge, and a lateral extension, provided with a curved edge, of proper contour and inclination, projecting from one end thereof, to produce an instrument of the character aforesaid. The curvature of the 45 edge is made in accordance with certain mathematical calculations and principles.

The nature of the invention will be fully understood from the following general description and the annexed drawings, and 50 will be subsequently pointed out in the claims.

In the accompanying drawings, which are hereby made a part of this specification, Figure No. I. is a side view of my newly 55 invented instrument. Fig. No. II. is an

illustration showing how the instrument is used.

T. designates the straight line ruler. The edge $b b'$ of this ruler is graduated. These 60 graduations may be as illustrated, or in any other desirable and available divisions. I. designates a lateral extension on said ruler, projecting from the end of the graduated edge. This projection has one curved edge i and one straight edge, the meeting point of 65 the curved and graduated edges being designated as "O." The straight edge is directly at right angles to the graduated edge $b b'$ of the ruler, and is cut with a notch at b . Each of said graduations is equal to the distance 70 $O b$. The curved edge i of this extension is a polysecting curve and is formed by a mathematical method and in accordance with the divisions it is to make.

I will illustrate the principle upon which 75 my device for dividing angles into equal parts is founded. To my invention I apply the principle of a curve drawn as the geometrical locus of vertices of triangles, whose angles at the base are in a ratio $1/n$. The 80 instrument for drawing any required curves as geometrical loci of vertices of triangles whose angles at the base are in a ratio $1/2$, $1/3 \dots 1/13 \dots 1/n$, is not described or 85 illustrated, but its use in connection with my invention is herein set forth.

If upon the given straight line A F, Fig. II, two permanent points O and A(b) are taken and through O in relation with another respective point d' , one has constructed 90 the curve i as the geometrical locus of vertices of triangles, whose angles at the bases upon the line A F are in a ratio $1/13$, any angle E A F is geometrically divisible by 13.

Curve i , as drawn in relation with d' , is 95 the geometrical locus of vertices of triangles, whose angles at the base A d' are in a ratio $1/13$.

Let the curve i intersect E A at point d and connect d with d' ; then triangle $d d' A$ 100 has angle $d A d'$ equal to 13 angle $d d' A$ (by hypothesis), therefore the measure of angle $d d' A$ is angle $d A d'$ or is angle E A F.

To use my invention, suppose that it be 105 desired to divide the angle E A F, of Fig. No. II. into 13 equal parts; then if the edge $b b'$ of the ruler T. be laid upon the line A F so as to register with it through the whole length of the ruler and so that the point at 110

b., will register with the apex of the angle A., then the curve *i*. will intersect the line A E., at *d*. If then the point *d'*, fixed on my instrument by mathematical calculations, be marked on the line A F., and the points *d d'* be connected, the angle A *d' d* will be equal to 1/13 of the angle E A F.

The point O is definitely located on the straight edge at the base of the curve *i* and 10 the point *b* is also fixed and alines with said straight edge and is essentially the point with which the apex of the angle to be measured must always register when applying the instrument. It is also evident that with 15 a sufficient number of instruments, properly adjusted and graduated a draftsman may quickly and easily obtain any desired aliquot part of any angle. When one aliquot part has been obtained the other aliquot parts of 20 the angle can easily be laid off, in the common and well known way. I do not however confine myself strictly to the contour and the arrangement of the instrument hereinbefore described as it is evident that under 25 the spirit of my invention I am entitled to all such variations of contour and arrangement as do not depart therefrom.

Having now ascertained and described what my invention is, and how the same is 30 constructed and used, what I claim, and desire to secure by Letters Patent is:

1. A ruler comprising a graduated straight edge, a pointed extension having one straight edge and one edge in the form 35 of a projecting curve, the contour of which is derived by mathematical calculation so as to have a fixed relation with reference to said graduated edge and projecting laterally from one end of the latter, and a determined 40 distance between the meeting points of the two edges of said extension with the straight edge.

2. As a new article of manufacture, an instrument for measuring the aliquot parts 45 of angles, comprising a ruler having a graduated straight edge and a point extension

projecting laterally from one end of said edge and comprising one straight notched edge at right angles to said graduated edge and the other edge of said extension in the 50 form of a polyseeting curve inclined to both of said edges, two fixed points upon the edge of the instrument one at the base of said curve and the other at the adjacent end of the instrument and having a determined 55 distance therebetween and the distance between each graduation and one of said points being a multiple of said intervening distance.

3. In an instrument of the class described 60 comprising a ruler provided with a graduated straight edge, a projection having one curved and one straight edge, said straight edge extending at right angles to said graduated edge and having a notch in alinement therewith, the curve of said curved edge being such as to locate the vertices of triangles whose base angles at two given points on the graduated edge have predetermined 65 ratio.

4. A ruler provided with a graduated straight edge, having a lateral end projection with one straight ungraduated edge and one curved edge meeting at a point, said straight edge alining with the end of said ruler and extending at right angles to said graduated edge, the straight edge of said extension having a notch at its point of meeting with the end of said ruler, the contour of said curved edge adapted to locate 75 the vertices of all triangles whose base angles at two given points of said graduations have a predetermined ratio.

In testimony whereof, I have signed my name to this specification in the presence of 85 two subscribing witnesses, this twenty-second day of January 1907.

JOSEPH SAMSONOFF.
